SURGICAL SPLINT

Lawrence A. Wilson, Temple Hills, Md., assignor
of one-half to Thomas H. Armstrong, Silver
Spring, Md.

Application April 21, 1947, Serial No. 742,772

2 Claims. (Cl. 128—84)

1

This invention relates to a surgical splint and has for its primary object to apply traction to a fractured femur and to support the limb in a position most comfortable for the patient.

Another object is to enable a patient to move from place to place without in any way interfering with the proper treatment of the fractured femur.

The above and other objects may be attained by employing this invention which embodies among its features a frame, a cradle in said frame for supporting the limb having the fractured femur, an arch at one end of the frame for engaging the hip of the patient having the fractured femur, a column rising from the opposite end of the frame and means attached to the column for exerting tension on the femur at a point remote from the end embraced by the arch.

Other features include means to adjust the angle at which the limb is supported in the frame, means to adjust the angle at which the traction is applied and means to regulate the degree of tension exerted on the femur.

Still other features include a wheel frame pivoted to the frame near the end from which the column rises and wheels on the wheel frame remote from the pivoted end thereof adapted when the wheel frame is moved out of parallelism with the frame to render the splint mobile and to hold the splint elevated when the patient is seated in a chair.

In the drawings:

Figure 1 is a perspective view of a surgical splint embodying the features of this invention,

Figure 2 is a side view of the splint illustrated in Figure 1,

Figure 3 is an end view from the rear end of the splint,

Figure 4 is a plan view of the splint,

Figure 5 is an end view of the splint taken from the end opposite that illustrated in Figure 3.

Figure 6 is a fragmentary enlarged sectional view taken substantially along the line 6—6 of Figure 4,

Figure 7 is a fragmentary enlarged sectional view taken substantially along the line 7—7 of Figure 1,

Figure 8 is a fragmentary enlarged sectional view taken substantially along the line 8—8 of Figure 4, and

Figure 9 is a fragmentary enlarged sectional view taken substantially along the line 9—9 of Figure 2.

Referring to the drawings in detail, a main frame designated generally 10 comprises a pair of spaced parallel angle bars 11 forming the side bars of the device, the forward ends of which are connected by a transversely extending end bar 12. Fixed to the vertical flanges of the angle bars 11 at longitudinally spaced points are bows 13, 14 and 15 which arch upwardly and extend transversely of the frame 10 to cooperate with the end bar 12 in holding the side bars 11 in

2

spaced parallel relation. As illustrated in the drawings the bows 13, 14 and 15 increase in height progressively from the rear end of the frame toward the forward end thereof, and pivoted in the upper end of the bow 15 and extending forwardly and upwardly therefrom is a yoke 16, the legs of which converge and terminate in spaced parallel extensions 17 between which a pulley wheel 18 is mounted to rotate about an axle 19. The ends of the legs of the yoke 16 opposite those pivoted to the arch 15 are joined by a bight portion 20 which is pierced to receive an attaching rivet 21 which supports a wheel guard 22 and a depending arm 23 the purpose of which will be more fully hereinafter explained. Extending forwardly from the cross bar 12 midway between opposite ends thereof is a bracket arm 24 carrying at its extreme forward end a column or pedestal 25 which is provided with a longitudinally extending elongated slot 26 for the reception of an adjusting bolt 27. This bolt 27 extends through the lower end of the depending arm 23 and is equipped with a wing nut 28 by means of which the vertical position of the arm 23 on the column or standard 25 may be adjusted, and hence the height of the pulley 18 from the frame 10 may be regulated. Fixed to the column or standard 25 near its lower end is a spindle 29 upon which is mounted to rotate about an axis which lies perpendicular to the axis of the pulley 18 a guide pulley 30 the purpose of which will be more fully hereinafter explained. Mounted on a spindle 31 carried adjacent one side bar 11 of the frame 10 to rotate about a vertical axis is a guide pulley 32, the periphery of which lies substantially tangential to the periphery of the pulley 30 as will be readily understood upon reference to Figure 1. Formed in each leg of each bow 13, 14 and 15 is a vertical row of vertically spaced apertures 33 the purpose of which will be more fully hereinafter explained.

A cradle designated generally 34 comprising a pair of side bars 35 and a sling 36 is mounted for adjustment between the bows on suitable bolts 37 which project through certain of the openings 33, and attaching clips 38, which bolts are provided with wing nuts 39. It will thus be seen that by loosening the wing nuts 39 and removing the bolts 37 from the apertures 33, and replacing them in different apertures and again tightening the wing nuts, the angular position of the cradle 34 may be varied to suit the comfort of the patient. Extending transversely between the rear ends of the side bars 35 is an arch 40 of relatively rigid material which is equipped with an arched hip engaging cuff 41 which is adapted to engage the hip of the patient to be treated.

An auxiliary cradle 42 is supported between the bows 14 and 15 and like the cradle 34 comprises side bars 43 between which is suspended a sling 44 for supporting the lower portion of

the limb of the patient. Like the cradle 34, the cradle 42 is capable of being adjusted vertically and angularly with relation to the frame 10.

Trained over the pulleys 18, 30 and 32 is a tension cable 45 carrying at one end a U-shaped yoke 46 which is adapted partially to embrace the limb under treatment and this yoke is pierced to receive a skeletal pin 47 which is extended through the femur in a well known surgical manner. The end of the cable 45 opposite that to which the yoke 46 is attached is coupled as at 48 to an elastic cord 49, the opposite end of which is extended through a tubular guide 50 secured as by clips 51 to the lower ends of the legs of the bows 13 and 14 and is attached by a suitable coupling 52 to a tension indicating device to be more fully hereinafter described.

The indicating device above referred to designated generally 53 comprises a tubular housing 54 provided adjacent one end with an annular outwardly extending bulged portion 55 for engagement against the end of the tubular body 56 as will be readily understood upon reference to Figure 6. Fixed as at 56 to a cross pin extending transversely through the tubular body 54 adjacent the end opposite the bead 55 is one end of a retractile coil spring 57, the opposite end of which is connected to the coupling 52 as shown. The body 54 is provided with a longitudinal slot 58, and fixed to a convolution of the spring 57 intermediate its ends is a pointer 59 which extends outwardly through the slot 58 to cooperate with indices marked on the exterior of the tubular body 54 along opposite sides of the slot 58. It will thus be seen that as the coupling 52 on the end of the cord 49 moves longitudinally of the body 56 its movement will be registered by the movement of the pointer 59 along the indicator 53. In this way the surgeon in charge of the case may determine the amount of tension being applied to a limb under treatment.

In order that the splint may be rendered mobile and elevated for the comfort of a patient when seated in a chair I pivot as at 60 to opposite side bars 11 near the forward ends thereof a pair of spaced parallel arms 61 of a wheel frame designated generally 62. The ends of the arms opposite those connected by the pivots 60 to the side bars 11 are held in spaced parallel relation by a cross member 63 and mounted on spindles 64 carried by the arms 61 adjacent the ends opposite the pivots 60 are wheels 65 which when the frame 62 is turned downwardly are adapted to contact the floor and support the frame 10 in spaced relation therewith. In order to hold the wheel frame 62 to properly support the frame 10 in spaced relation to the floor suitable stops 66 are attached to the arms 61 near the pivot points 60 which when the wheel frame 62 assumes the position illustrated in Figure 2 with relation to the frame 10 engage the under faces of the bottom flanges of the side bars 11 so that as the patient is advanced along the floor or seated in a chair, the parts will be held in proper position. On the other hand the main frame 10 is supported on a bed and the patient is in a reclining position the wheel frame is folded as illustrated in Figure 1 so that the arms 61 lie parallel with the side bars 11 of the main frame 10.

In use the limb to be treated is placed in the cradles 34 and 42 with the side bars 35 arranged at the desired angle and adjusted so as to bring the cuff 41 into contact with the trunk at its junction with the limb. The skeletal pin is then introduced into the limb in a well known manner

and the cable 45 is coupled with the yoke 46, so that the elastic cord 49 will be extended, and will exert pull on the femur being treated. The couplings 48 and 52 detachably connect the elastic cord 49 to the cable 45 and to the spring 57, and by interchanging elastic cords different degrees of tension will be exerted on the femur. The amount of tension exerted by the elastic cord 49 on the femur may be easily determined by the position of the pointer on the scale appearing on opposite side of the slot 58 and the degree of tension may be varied by interchanging the elastic cord with a more or less powerful one. The device not only will serve to exert traction on the femur of a patient in reclining position, but where conditions will permit the patient may be moved, and may even be allowed to sit up by moving the wheel frame 62 downwardly and supporting the forward end of the main frame 10 thereon to thus relieve the patient of much of the discomfort ordinarily attending the prolonged application of traction to fractured femurs. The adjustment of the cradles 34 and 44 will enable the limb to be supported in the most comfortable position and by adjusting the height of the pulley 18 it is obvious that the angle at which pull is exerted on the femur may be easily varied.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. A surgical splint for applying traction to a fractured femur comprising a frame having elongated side bars, longitudinally spaced vertically extending, inverted U-shaped braces secured to said side bars, limb supporting cradles each having side sleeves, side bars received in said sleeves, means mounting said rods for vertical adjustment on said braces, and means carried by said frame for exerting tension on the femur, said first-named means including attaching clips engaging each of said side rods, the legs of said braces being provided with vertically spaced apertures, and an adjusting screw extending through each clip and through a selected one of said apertures.

2. The combination of claim 1 and a second frame having side members, wheels carried at one end of said side members, means securing the other end of said members to said side bars for movement in a vertical plane relative to said first-mentioned frame, and stops carried by said other end of said side members and engageable with said side bars for retaining said first-mentioned frame in a desired elevated position on said wheels.

LAWRENCE A. WILSON.
